UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY-CAR.

1,399,755.

Specification of Letters Patent. Patented Dec. 13, 1921.

Application filed April 21, 1921. Serial No. 463,315.

To all whom it may concern:

Be it known that I, THOMAS ELLIOTT, a citizen of the United States, residing at Cincinnati, in the county of Hamilton and State 5 of Ohio, have invented certain new and useful Improvements in Railway-Cars, of which the following is a specification, reference being had therein to the accompanying drawing.

10 This invention relates to double-ended one man railway cars, particularly of the class used on lines, one terminal of which is in the crowded or congested part of the city and the other terminal in a suburban or less 15 congested or crowded district.

In my application filed March 21st, 1921, Ser. No. 454,030, I set forth and claim a one man double-ended or two way car to be used under the aforesaid conditions with a double 20 system of signs and doorway controls or gates and doors for the doorways arranged and operated in a manner to permit of one side of the car being used on the system of "pay as you enter", as when leaving a sub- 25 urban district or locality where the traffic is uncongested and scarce, and to permit the other side of the car to be used as a "pay as you leave", car, as when the car leaves a terminal where conditions of traffic are 30 crowded.

In my present invention I do away with the feature of mechanism to operate or change and set the signs, and instead I combine with the other features of doorways, 35 doorway controls or gates, and doors, signs which are stationary or fixed in the sense that when they are once placed in their respective positions, as by hand, or by painting them, they will function without adjustment 40 during the use of the car in receiving and letting off passengers.

To these ends I employ what I term "stationary" signs over or near the doorways, both outside and inside of the car, as the 45 words "entrance" and "exit", and this I do in this wise—over the front doorway for the admission of passengers I place the legend "Entrance" and over the rear doorway for the departure of passengers the legend 50 "Exit", and vice versa on the other side of the car, so arranged that the word "Entrance" and the word "Exit" will appear on both sides, the positions of the word "En-

trance" being at opposite sides on the same end and likewise the word "Exit" at opposite 55 sides on the same end.

And in those cases, such as illustrated herein, where the cars have double doorways, that is, very wide doorways occupied by a pair of doors, then while the word "En- 60 trance" will be associated with a part of such doorway, the word "Exit" will be associated with the other part, so that such wide doorway may be used both for entrance and exit, if desired, but in such case only one such 65 door may be opened at a time, say the one under "Entrance" or the one under "Exit", according to circumstances.

In the accompanying drawings,

Figure 1 is a side elevation of a car em- 70 bodying my invention;

Fig. 2 is a plan view thereof;

Fig. 3 is a vertical sectional view of the upper portion of a car looking at the inside of that side shown in Fig. 1; 75

Fig. 4 is a side elevation of the opposite side of the car to that shown in Fig. 1;

Fig. 5 is a sectional view of the upper part 80 of a car looking at the inside of that side shown in Fig. 4;

Fig. 6 is a detail enlarged sectional view through that portion of the car on which the signs are placed above the doorway;

Fig. 7 is a plan view in the nature of a 85 diagram showing the arrangement of the door-operating mechanism.

I will first describe my invention with reference to its use on cars "on the pay as you enter system", and will then later set forth its use on the "pay as you leave" 90 system, and will finally refer in detail to the arrangement of the mechanism employed in carrying out the use of cars on both of these systems.

As shown in Fig. 1, the car is to be used 95 on the "pay as you enter" system and it will be assumed that it is in a suburban or uncrowded district and is about to make a trip to a city terminal, the right hand end, as shown in Fig. 1, being now the front end 100 of the car. Over the double doorway 1 controlled by doors 2 and 3 are the words "En- trance" and "Exit". At the other end of the car over the single doorway 4 controlled by a single door 5 is the word "Exit". The 105 same legends appear also on the inside of

that side of the car, as indicated in Fig. 3. From Fig. 6 it will be seen that an outer sign board or surface 6 is provided for the outside legends while a panel 7 affords a surface for the display of the inside legends.

Looking at Fig. 2 it will be seen that a motorman's stand is indicated at A and a fare box at B at what is now the forward end of the car, while at the other end, which 10 on the return trip will be the forward end, a motorman's stand is indicated at C and a fare box at D.

When passengers are to board the car in a suburban or uncrowded district they will 15 do so under the legend "Entrance" which will be open to them by the opening of the door 2 by the motorman, through mechanism to hereinafter appear. As conditions here are not crowded and the passengers are 20 not pressed for time and space, they will deposit their fare, under the observation of the motorman, in the fare box B and will then take their seats. Later when they are 25 to leave the car they will do so under the word "Exit" at the rear, for which purpose the motorman will open the door 5. The doorway controls, generally indicated at 8, are now set with their arms projecting outward inviting the passengers to push them 30 aside and pass out. These arms will yield outward when set in the position shown in Fig. 2 and will return to their normal position because they are spring mounted. The construction of these controls is fully 35 set forth and described in my copending application filed March 21st, 1921, Ser. No. 454,081.

Under some conditions, as when the car 40 is very much crowded and it is desired to have the passengers exit more rapidly, the doorway 3 under the legend "Exit" may be opened at the same time as the door 5 at the other end.

And now let it be assumed that all the 45 passengers have left the car and that it is in a crowded or congested district or terminal and is about to be boarded by passengers. Under these conditions the "pay as you leave" system will be employed. The 50 front of the car will now be that shown at the left in Fig. 2 and the side of entrance will be the upper side shown in Fig. 2, which in Fig. 4 is illustrated in elevation.

As conditions are crowded, the door 9 of 55 the double doorway 10 will be opened under the word "Entrance", the door 11 under the legend "Exit" not being now employed. And the door 12 in the doorway 13 under the legend "Entrance" will also be opened. 60 In this way passengers will hasten in from both ends of the car without paying their fares. When, however, they are to leave the car and as they do so from time to time which avoids crowding, the door 11 will be 65 opened for them by the motorman and they

will pass out under the legend "Exit", which, of course, appears on the inside as well as the out. As they do so they will pay their fares in the fare box D under the observation of the motorman who now is at 70 station C.

As the doorway controls or gates 14 stands with their arms in a position to open inward, these arms were readily swung aside by the passengers as they entered when the door 12 75 was opened to them, as above stated. It is observable at this point that as the doorway 4 with its door 5 under the word "Exit" is always a means of exit, therefore the control arms or gates bow outward, while as 80 the doorway 13 with its door 12 is always for entrance the control arms or gates always bow inward.

Thus it will be seen that I have provided a double-ended one-man car in which the legends indicating entrance and exit are fixed 85 in the sense of being so arranged and assigned to the respective doorways and portions thereof, (in the case of double doorways) as to direct the passengers both for 90 entrance and exit and as well when the car is leaving suburban or uncrowded district and departed from in congested terminals or sections, and vice versa, as when boarded in crowded sections. And also that by reason 95 of the controls the passengers are prevented from accidentally or purposely starting or attempting to pass out of a doorway which is for entrance, as at 14, or in a doorway which is for exit, as at 8, should it happen, 100 by design or accident, that the doors at such doorways are open, momentarily or otherwise.

And it will also be observed that not only 105 are these facilities afforded whereby a one man car may be utilized as a double ended car, but that the passengers are also afforded the most explicit and conspicuous instruction as to the course they are to take in boarding and leaving the car, whereby rapid 110 loading is made possible in congested districts with payment as the passengers leave, and whereby passengers board the car in uncrowded districts, paying their fare as they do so.

Referring now to one form of mechanism 115 for operating the doors, I would call attention to Fig. 7, a detail description of which is as follows:—

An air pressure tank 15 connects by a pipe 120 16 a cross branch 17, a valve 18 and pipes 19 and 20 with an air engine 21 whose piston (not shown) operates a crank arm 22 to which are connected a pitman 23 attached to a crank arm 24 connected with the door 2; 125 and to a pitman 25 connected by a crank arm 26 with the door 3.

By turning the handle of the valve 18 to a position near the word "Open" air will be admitted from the tank 15 to the engine 21

and the doors 2 and 3 will be opened. By turning the valve handle to the position indicated by the word "Close" air will be admitted to the other end of the engine 21 and 5 the doors 2 and 3 will be closed.

Standing at or near the same place the motorman may open and close the door 5 on the same side of the car by turning the handle of the valve 27 to a position near the 10 word "Open" when the air will pass from the branch pipe 17 through the valve and through the pipe 28 into the engine 29 and operate the contained piston to swing the crank 30 and through the pitman rod 31 actuate the crank arm 32 connected with the door 5 and open the door. By swinging the handle of the valve 27 to near the word "Close" the air will pass through the pipe 33 and enter the other end of the engine 29 and 20 close the door 5.

Now to open and control the doors 9, 11 and 12 on the other side of the car when the motorman is standing at the left hand end, as viewed in Fig. 7, he will turn the handle 25 of the valve 34 near the point marked "Open" when air will flow from the tank 15 through the pipe 35, the branch pipe 36, the valve 34 and the pipe 37 into the engine 38 which will actuate the piston to turn the 30 crank arm 39 and push on the rod 40 which through the arm 43 will open the door 11 and likewise push on the rod 42 which through the arm 41 will open the door 9.

When the handle of the valve 34 is turned 35 to the position indicated by the word "Close" the air will pass from the valve 34 through the pipe 44 and into the engine 38 and thereby close the doors 9 and 11. To operate the remote door 12 the motorman will 40 turn the handle of the valve 45, to the point indicated by the word "Open" which will cause air to flow through the pipe 46 to the engine 47 to actuate the piston to move the crank 48 and push the rod 49, which through 45 the arm 50 will open the door 12.

To close this door the motorman will present the handle of the valve 45 near the point indicated by the word "Close" which will permit the air to pass through the pipe 51 to the other end of the engine 47 and cause 50 the piston and crank arm 48 to pull on the rod 49 and through the arm 50 close the door 12.

The mechanism here described for these 55 several purposes is illustrative only and, while perfectly feasible, may be modified or be dispensed with and other mechanism employed for like purposes. Again, it will be noted, that while this conventional door operating mechanism here described will open and close the pair of doors in each wide doorway, still this operating mechanism may be modified so as to open and close but one of said double doors at a time.

65 Having thus fully described my invention,

what I claim as new and desire to secure by letters patent, is:—

1. A double-ended one-man car having front and rear doorways at each side thereof, and signs for said doorways, the signs on 70 one side comprising an entrance legend at one doorway and an exit legend at the other doorway, and the signs on the other side comprising an exit legend at one doorway and an entrance legend at the other, so that such car 75 may be used on the "pay as you enter" system when the entrance legend is at the front doorway and the exit legend at the rear doorway or on the "pay as you leave" system when the entrance legend is at the rear doorway and the exit legend at the front doorway.

2. A double-ended one-man car having front and rear doorways at each side thereof, and signs for said doorways, the signs on one 85 side comprising an entrance legend at one doorway and an exit legend at the other doorway, and the signs on the other side comprising an exit legend at one doorway and an entrance legend at the other, so that such car 90 may be used on the "pay as you enter" system when the entrance legend is at the front doorway and the exit legend at the rear doorway or on the "pay as you leave" system when the entrance legend is at the rear doorway and the exit legend at the front doorway, doors for said doorways, a doorway control for one door on each side, and operating mechanism for said doors.

3. A double-ended one-man car having 100 front and rear doorways on each side, one doorway on each side being double and the other single, an entrance and an exit legend for the double doorway on one side and an exit legend for the single doorway on the same side, and an exit and entrance legend for the double doorway on the other side and an entrance legend for the single doorway on that side so that such car may be used on the "pay as you enter" system when the entrance 110 and exit legends are at the front double doorway and the exit legend at the rear single doorway or on the "pay as you leave" system when the exit and entrance legends are at the front double doorway and the entrance 115 legend at the single rear doorway.

4. A double-ended one-man car having front and rear doorways on each side, one doorway on each side being double and the other single, an entrance and an exit legend 120 for the double doorway on one side and an exit legend for the single doorway on the same side, and an exit and entrance legend for the double doorway on the other side and an entrance legend for the single doorway on that side so that such car may be used on the "pay as you enter" system when the entrance and exit legends are at the front double doorway and the exit legends at the rear single doorway or on the "pay as 130

you leave" system when the exit and entrance legends are at the front double doorway and the entrance legend at the rear single doorway, doors for said doorways, a doorway control for one doorway on each side, and operating mechanism for said doors.

5. A double-ended one-man car having on opposite sides at diagonal positions double doorways, each doorway having sign legends

for entrance and exit and on each side single doorways at opposite diagonal points, one of said latter doorways having the legend "Exit" and the other the legend "Entrance," doors for said doorways, and doorway controls for said single doorways, one control opening outward and the other inward.

In testimony whereof, I affix my signature.
THOMAS ELLIOTT.
